CONTROL DEVICE

Harold Arthur Wheeler, Grand Rapids, Mich., assignor to Bendix Aviation Corporation, Teeterboro, N. J., a corporation of Delaware

Application September 26, 1945, Serial No. 618,742

8 Claims. (Cl. 123—25)

1

The present invention relates to improved control devices and systems of the class disclosed by application Serial No. 783,237, filed October 31, 1947, by Howard A. Alexanderson as a continuation of application Serial No. 508,724, filed November 2, 1943, and application Serial No. 551,036, filed August 24, 1944, by Howard A. Alexanderson. More specifically, the present invention relates to a novel and improved control mechanism for a supercharged aircraft engine which provides means for effecting automatic control of two intake manifold pressure selection programs for such an engine in response to an operating condition thereof.

An object of the invention is to provide novel means responsive to the intake manifold pressure for adjusting a throttle valve so as to approximate predetermined pressure values together with a single adjustable member for selecting such pressure values and means for selectively actuating said member into operating relation in response to an operating condition.

Another object of the invention is to provide a novel adjustment means for directly actuating an automatic carburetor throttle control in a first sense, and a second novel intake manifold pressure responsive means for directly actuating the throttle control in an opposite sense so as to maintain a predetermined selected pressure value, which value is variable in accordance with a first selected program, and adjustable means for varying such value in accordance with a second selected program.

Another object of the invention is to provide a novel selector linkage arrangement, whereby the datum of the boost control may be selected in accordance with two predetermined programs.

Another object of the invention is to provide a novel control mechanism for selecting in accordance with a first selected program the intake manifold pressure of the aircraft engine, including novel adjustable means for varying the relationship of the intake manifold pressure of the aircraft engine in accordance with a second selected program brought into operation by a predetermined operating condition.

During operation of the so-called "water" or "anti-knock" fluid injection systems for suppressing pre-detonation in internal combustion engines, an increase in the air inlet pressure of the induction system for the engine is permissible and desirable in order that greater engine power may be obtained than when such injection system is not in operation. Therefore, an object of the invention is to provide a novel regulator respon-

2

sive to operation of such an injection system for effecting a predetermined increase in the air pressure in the induction system.

Another object of the invention is to provide a novel regulator for effecting smooth control throughout the range of operation of the "anti-knock" fluid injection system.

These and other objects of the invention are pointed out in the following description in terms of the embodiment thereof which is shown in the accompanying drawings. It is to be understood, however, that the drawings are for the purpose of illustration only, and are not designed as a definition of the limits of the invention, reference being had to the appended claims for this purpose.

In the drawings:

Figure 1 is a sectional view showing the control mechanism;

Figure 2 is a sectional view taken along the lines 2—2 of Figure 1;

Figure 3 is a schematic view showing the control mechanism in operative relation with the aircraft engine controlled thereby;

Figure 4 is a diagrammatic view of the operating mechanism; and

Figure 5 is an enlarged view of the linkage arrangement for the cam follower arm.

The control mechanism as shown in Figures 3 and 4 is preferably operated by a main control lever 1 pivotally mounted at 2 within the cabin of an aircraft. There is pivotally connected to the control lever one end of a main control rod 3.

As shown in Figure 4, there is pivotally connected at the opposite end of the main control rod 3 at 4, an arm 5 mounted on a main control shaft 6 and positioned exteriorly of a casing 7 as shown in Figures 3 and 4. The casing 7 houses the novel control mechanism and may be conveniently mounted on a bracket 7A as shown in Figures 1 and 3.

As shown in Figures 3 and 4, there is formed integral with the arm 5, a second arm 8 likewise mounted on the main control shaft 6 and positioned exteriorly of the casing 7. Movement of the arm 8 may be limited as indicated in Figure 3 by a stop 9, which is arranged for engagement by an adjustable limiting screw 9A provided on the arm 8 and a second engaging arm 10 formed integral with the arm 8.

The main control shaft 6 extends into the casing 7 and is rotatably mounted on suitable anti-frictional roller bearings, not shown.

Positioned within the casing 7 and fixedly mounted at the inner end of the main control

shaft 6 is a crank pin 11, as best shown in Figures 1 and 4. The crank pin 11 has pivotally mounted at the free end thereof a walking beam 12. The walking beam 12 is pivotally connected at one end to a link 13 which is in turn pivotally connected at the other end to an arm 14 of a bell crank lever 15, as shown in Figures 1 and 4. The bell crank lever 15 is mounted on a shaft 16.

The shaft 16 is mounted on anti-frictional roller bearings, not shown, and projects through the casing 7, as shown in Figure 4. Mounted at the outer end of the shaft 16 is an arm 17 having pivotally connected at the free end a throttle control rod 18 for adjustably positioning a throttle valve 19 positioned within the air intake conduit of a conventional aircraft internal combustion engine, as indicated diagrammatically in Figure 3.

The throttle valve 19 is arranged so as to regulate the pressure at the intake manifold 20 of an engine 21 by regulating the air inlet through conduit 22 to a supercharger 23. The supercharger 23 is driven by the aircraft engine 21 through a drive shaft 25. The supercharger 23 is arranged to supply air to the intake manifold 20. A carburetor 27 is provided on conduit 22 of conventional type and a conduit 28 leads from the carburetor 27 to a suitable air supply or air intake scoop 29.

Pivotally connected to the arm 8, previously described, is one end of a linkage rod 30. The opposite end of the rod 30 is pivotally connected to one end of a lever arm 31 mounted on a pressure selector shaft 32, as shown in Figures 2 and 4. The shaft 32 projects into the casing 7 and 15 preferably mounted therein on bearing 32A.

The shaft 32 has fixedly mounted at the inner end thereof a cam 33 which may be adjustably positioned by the adjustment of the shaft 32. The cam 33 has provided variable cam surface 34 which is arranged to bear upon a cam follower member 35.

The cam follower member 35 projects from the lower end of a lever 36 pivotally supported intermediate its opposite ends by a pin 37 carried by an arm 38. As shown in Figures 2 and 5, the arm 38 is pivotally mounted at the lower end on a pivot pin 39 which projects through a suitable opening 40 formed in the lever 36. The pivot pin 39 is eccentrically affixed to an adjustment screw 41 carried by the casing 7.

A tension spring 42 is coiled about the pin 39 and has one end 43 held securely by a portion 44 of the casing 7. The other end 45 of the spring 42 bears upon the lower end of the lever 36 and tends to bias the lever 36 in a counter-clockwise direction about the pivot pin 39 carried by the arm 38 and the member 35 into contacting relation with the cam surface 34.

The upper end 46 of the arm 38 is operably engaged by one end of a rod 47 for shifting the position of the pivot pin 37 of the lever 36 for a purpose which will be explained hereinafter.

It will be seen from the foregoing arrangement that upon inward adjustment of the rod 47 to the left, there will be imparted a counter-clockwise movement to the arm 38 about the pin 39 which will cause in turn the pivot pin 37 for the lever 36 to shift in a counter-clockwise direction about the fixed pivot 39. Movement of the pivot pin 37 causes the lever 36 to likewise shift in a counter-clockwise direction about its cam engaging member 35 against the biasing force of the spring 42. The opening 40 permits movement

of the lever 36 relative to the pin 39 during the latter operation.

Moreover upon the rod 47 being adjusted in an opposite direction the spring 42 applies a force through the spring end 45 to the lever arm 36 which tends to bias the same in a clockwise direction about its lower cam engaging end member 35 which causes the pivot 37 to shift in a clockwise direction about the fixed pivot 39. Thus the arm 38 under force of the spring 42 moves in a clockwise direction about the fixed pivot 39 and follows the movement of the rod 47 to the right. The opening 40 permits the return movement of the lever 36 under the biasing force of the spring 42 as the pivot pin 37 is shifted in a clockwise direction about the fixed pivot 39 during the latter operation of the rod 47.

The upper end of the lever 36 is moreover pivotally connected to one end of a floating lever 50. The floating lever 50 is pivotally connected at an end 51, to one end of a linkage arm 52. The linkage arm 52 is operatively connected at the opposite end to a pressure responsive mechanism indicated generally by the numeral 53 which will be hereinafter described.

Servo-motor mechanism

A third link 54 is pivotally connected to the floating lever 50 at a point intermediate the opposite ends of the lever 50. The opposite end of the link 54 is affixed to a slidably adjustable member 56 for controlling a servo-valve of conventional type. As shown in Figure 1, the member 56 is slidably mounted within a valve sleeve 56A positioned within the wall of the casing 7. Carried by the servo-valve control 56 is a tension spring 57 which exerts a force biasing the link 54 toward the floating lever 50. The valve sleeve 56A has provided ports 58, 59, 60, 61 and 62, as shown in Figures 1 and 4. The ports 59 and 61 are connected by suitable conduits 63 and 64, respectively, to a servo-motor indicated generally by the numeral 65, while a conduit 66 is connected to the port 60 and serves as an inlet to the servo-valve of a suitable fluid medium under pressure such as oil under engine pressure for operation of the servo-motor 65. A drain conduit 67 is further connected to the ports 58 and 62 and serves as an outlet for the fluid pressure medium supplied to the servo-valve in the conventional manner.

As shown in Figures 1 and 4, a servo-piston 68 is slidably mounted within a cylinder wall 69 of the servo-motor 65. The piston 68 is connected to a piston rod 70 in any conventional manner. A tension spring 71 biases the piston 68 in a direction tending to slide the rod 70 outwardly from the cylinder 69 for a purpose which will be explained hereinafter. Movement of the piston 68 in response to the biasing force of the spring 71 is limited by a collar 72 against which the piston 68 abuts in the extreme biased position.

As shown in Figure 1, suitable telescoping tubular members 73 and 74 are provided for protecting the spring 71 and limiting the extent of movement of the piston 68 in the opposite direction.

The conduits 63 and 64, previously described, lead to opposite sides of the piston 68 so that adjustment of the servo-valve control 56 to the left of the neutral position shown in Figure 6, will cause the conduit 63 to serve as an inlet of pressure to the servo-motor 65 and thereby exert a

5 biasing force upon the piston 68 to the right. Likewise, adjustment of the servo-valve control 60 to the right of the neutral position shown in Figure 6, will cause the conduit 64 to serve as an inlet of pressure to the servo-motor 68 and exert biasing force upon the piston 68 to the left. Thus it will be seen that in the conventional manner the direction of movement of the piston rod 88 may be controlled by the adjustment of the servo control valve 56.

While there has been shown in the present embodiment of the invention a hydraulic control and power means, it will be readily seen that other forms of the controls and power means such as well known, mechanical and electronic controls and power means, may be readily substituted therefor.

It will be further noted that the outer end of the piston rod 70 under control of the power means aforesaid, is pivotally connected by a link 75 to the opposite end of the walking beam 12 from that at which the link 13 is connected, as previously described. It will thus be seen that the adjustment of the walking beam 12, and accordingly the throttle control shaft 16 is dependent upon the effect thereon of the adjustment of the main control shaft 6 and the servo-motor 65.

The adjustment of the servo-motor 65 is dependent upon the adjustment of the pressure selector cam 33, previously described; the position of the pressure responsive mechanism 53 as will be further described, in relation to the adjustment of the pressure selector cam; and upon the adjustment of the position of the pressure selector cam 33 or the pressure responsive mechanism 53, as will be explained.

Pressure responsive mechanism

The pressure responsive mechanism 53, previously noted, comprises preferably a pair of bellows 76 and 77 mounted within the casing 7, as best shown in Figure 1. The bellows 77 is preferably partially evacuated and balanced by a coil spring 78 mounted within the bellows 77 so as to act against the biasing force of the bellows 76. A wall 79 formed within the casing 7 has mounted thereon the bellows 76 which is connected through a passage 80 passing through the wall 79, and a conduit 81 connecting the passage 80 to the intake manifold 20 of the internal combustion aircraft engine 21, as shown in Figures 1, 3 and 4, in such a manner that the biasing force of the bellows 76 will vary in response to the intake manifold pressure. A plate 82 is mounted between the bellows 76 and 77 and is movable upon variance in the pressure exerted within the bellows 76, as is well known in the art. The plate 82 has provided a projecting arm 83 to which there is pivotally connected an end of the linkage arm 52 previously described. The opposite end of the bellows 77 is mounted on a plate 84 secured in the side wall of the casing 7 as shown in Figure 1.

From the foregoing it will be seen that the adjustment of the servo-valve control 56 will be dependent upon the intake manifold pressure acting upon the pressure responsive mechanism 53 and the corresponding adjustment thereof in relation to the adjustment of the operating cam 33. It should be pointed out here that the tension exerted by the spring 42 and acting upon the arm 36 has a considerably greater biasing force upon the servo control valve member 56 than the force exerted thereon by the relatively

6 light tension spring 57 mounted on the member 56.

Thus it will be seen that in normal operation a decrease in the intake manifold pressure due to a rise in altitude for example, decrease in atmospheric pressure or other cause, would affect the bellows 76 and 77 so as to cause the relative contraction of the bellows 76 and the relative expansion of the bellows 77. Such action would 10 cause the movement of the plate 82 and the longitudinal movement of the linkage arm 52 toward the left, as viewed in Figures 1 and 4.

Since, as previously explained, the spring 42 exerts a greater biasing force than the spring 57, 15 it will be readily seen that such longitudinal movement of the arm 52 would cause the floating lever 50 to pivot in a clockwise direction on its pivotally connection to the arm 36 resulting in a corresponding longitudinal movement of the link 54 and servo control valve member 56 to the left.

Thus with the control valve member 56 first in the neutral position, such adjustment of the servo control valve member 56 would cause the opening of the port 69 to the inlet of the pressure medium 23 provided through the port 60 resulting in the shifting of the piston 68 to the right as viewed in Figures 1 and 4 and the mechanical adjustment of the throttle 19 to a relative increased open position through the action of the piston rod 70 on the link 75, walking beam 12, link 13, bell crank lever 15, throttle control shaft 16, arm 17, and rod 18, and thereby increasing the pressure exerted at the intake manifold 20.

Conversely, an increase in the intake manifold 35 pressure would cause the relative expansion of the bellows 76 and contraction of the bellows 77, resulting in the longitudinal movement of the linkage arm 52 to the right.

Obviously, since the movement of the lever arm 40 36 would be prevented by the spring 42, the latter adjustment of the linkage arm 52 would cause the counter-clockwise movement of the floating lever 50 about its pivotal connection to the arm 36, causing a corresponding longitudinal movement 45 of the servo control valve member 56 to the right. Thus with the control valve member first in the neutral position, such adjustment of the servo control valve member 56 would cause the opening of the port 61 to the inlet of the pressure medium 50 provided through the port 60 causing a shifting of the piston 68 and the mechanical adjustment of the throttle 19 to a relative decreased open position and thereby decreasing pressure exerted at the intake manifold 20.

55 Thus it will be seen that there is provided automatic means for compensating for either an increase or decrease in the pressure at the intake manifold 20, so that a predetermined standard pressure condition may be approximated. Obviously, upon standard pressure conditions being approximated, the pressure responsive mechanism 53 will cause the adjustment of the servo control valve member 56 to a neutral position.

60 It will be further seen that there has been provided adjustment means whereby the value of the predetermined standard pressure condition may be varied. Thus upon movement of the control lever 4, as shown in Figure 4, in a counter-clockwise direction, a clockwise movement of the main control shaft 6 will result, causing a corresponding clockwise movement of the walking beam 12 about its pivotal connection to the link 75 and causing in turn the clockwise movement of the throttle control shaft 16 so as to move the throttle 70 19 to a relative open position.

Furthermore, it will be seen that such adjustment of the control arm 1 will cause also the clockwise movement of the arm 8 and a corresponding clockwise rotation of the cam 33, as viewed in Figure 4, for changing the datum or setting of the pressure responsive mechanism 53.

Pressure selection mechanism

It will be noted that as the lever member 1 of Figure 4 is moved in a counter-clockwise direction, the pressure setting of the bellows 53 is increased by causing the lever 36 to be adjusted in a counter-clockwise direction about the pivot 37. Thus the highest pressure setting is obtained at the lowest rise of the cam surface 34, while the lowest pressure setting results at the highest cam rise.

Further, upon adjustment of the rod 41 to the left, the pivot 37 is shifted in a counter-clockwise direction about the pivot 39 so as to effect a second higher pressure setting program.

This latter higher pressure setting program is likewise adjusted through the operation of the cam 33 under the control of the lever 1.

Water injection system

As best shown schematically in Figure 3, there is connected to the carburetor 27 a conduit 100 leading from a suitable source of fluid fuel for the aircraft engine. There is also provided a conduit 101 for injecting the fuel into the induction system through a nozzle 102. There is further provided a conduit 103 for injecting into the induction system through nozzle 102 a supplemental or so-called "anti-knock" fluid medium such as water, water-alcohol or other suitable fluid well known in the art for suppressing predetonation of the engine 21.

The conduit 103 is connected to a suitable metering device shown in dotted outline and indicated generally by the numeral 104. The latter metering device may be of suitable type well known in the art for determining the rate of flow of the "supplemental" fluid, and, since the herein invention resides in the regulator means rather than in the metering device, the same has been shown diagrammatically by the outline indicated by numeral 104.

A conduit 105 leads to the metering device 104 from a suitable source of "supplemental" fluid indicated by numeral 106. In the conduit 105, there is provided a pump indicated by numeral 107 driven by a suitable power means not shown. The pump 107 supplies the fluid medium under pressure to the metering device 104. A valve 108 is provided in the conduit 108 between the pump and the metering device 104 for "off" and "on" control of the "supplemental" fluid injection system. The control valve 108 may be of any suitable type, but is shown herein as of an electro-magnet controlled type having an electrical control circuit 109 and switch 110 which is preferably mounted within the aircraft cabin for convenient operation by the pilot. Thus the supplemental fluid injection system may be placed in operation by the pilot closing the switch 110 so as to effect the opening of the valve 108. Conversely, the valve 108 may be closed by opening the switch 110. A by-pass conduit 111 and relief valve 112 is provided for recirculating the fluid medium from the pump outlet to the pump inlet at such times as the valve 108 is closed and the injection system is not in operation.

A conduit 113 is connected to the conduit 105 between the valve 108 and the metering device 104. The conduit 113 leads to a control mecha-

nism 114 arranged so that during operation of the injection system, the rod 41 is shifted to the left by the pressure of the supplemental fluid medium acting under force of the pump 25, as will be explained hereinafter. It will be readily seen that when the injection system is in operation the fluid medium will exert through the conduit 113 a greater pressure under force of the pump 106 than when the injection system is not in operation.

Control mechanism responsive to operation of water injection system

The control mechanism indicated generally by the numeral 114 includes as shown in Figure 1, a plug or casting 115 which projects into the casting 1 and has slidably mounted therein the rod 47. Formed in the outer end of the casting 115 is a recessed chamber 116 open through a port 117 to atmosphere or other reference pressure.

Extending across the chamber 117 is a diaphragm 118 which is fastened in position between the outer end of the casting 115 and a casting 119 by bolts 120.

Formed in the casting 119 is a chamber 121 positioned at the opposite side of the diaphragm 118 from the chamber 116. The conduit 113 opens into the chamber 121 so as to subject the diaphragm 118 to supplemental fluid injection pressure when the latter system is in operation.

A spring 122 is provided at the opposite side of the diaphragm and normally biases the diaphragm 118 to the right when the water injection system is not in operation.

The rod 47 which bears at one end upon the arm 38 has its opposite end fastened to the diaphragm 118 by the fastening screw 123. There is also secured at the opposite side of the diaphragm 118 by the screw 123 an arm 124 which is arranged to engage a member 125 so as to limit the movement of the diaphragm 118 to the left.

The member 125 is affixed to an adjustable screw 126 screw threadedly engaged in a nut 127 rotatably mounted in the casing 119. The screw 126 is restrained from rotary movement relative to the casting 119 by a pin 128 which projects into the chamber 121 and engages the member 125.

The nut 127 is thus so arranged that convenient adjustment of the member 125 may be readily effected so as to determine the limit of movement of the rod 47 to the left under the biasing force of the supplemental fluid injection pressure.

A flange 129 is provided on the rod 47 so as to limit the return movement of the rod 47 to the right under force of the spring 122 upon the cessation of operation of the supplemental fluid injection system. The flange 129 engages a washer 130 mounted at the inner end of the casting or plug 115 and held in position by a suitable snap ring 131.

It will be readily seen from the foregoing that upon operation of the supplemental fluid injection system there is effected an increase in the fluid pressure exerted in the chamber 121. The diaphragm 118 under such increased pressure actuates the rod 47 so as to effect an adjustment of the arm 38 in a counter-clockwise direction shifting the pivot pin 37 and the lever 36. Thus there is effected an increase in the pressure setting of the bellows 53 for a given position of the control lever 1 during operation of the supplemental fluid injection system. The extent of such increase in pressure setting may of course, be conveniently varied through appropriate ad-

justment of the nut 121. Likewise the pressure may be conveniently adjusted during the latter operation by operation of the manual control lever 1.

Of course, upon cessation of operation of the supplemental fluid injection system, the rod 47 is returned under force of the spring 122 to the normal position and the arm 46 is biased under force of spring 42 to the position shown as previously explained.

Lock out limiting means

There is further provided means to lock out the automatic means, whereby upon adjustment of the main control lever 1, to a predetermined minimum standard pressure selection position, the opening of the throttle 19 may be affected only by the manual adjustment of the control lever 1 without regard to the pressure existing at the intake manifold or the condition of the pressure responsive mechanism. This is specifically accomplished by providing an adjustable abutment rod 135 best shown in Figures 1 and 4 and explained in detail in the copending application of Howard A. Alexanderson, Serial No. 508,724, filed November 2, 1943. The abutment rod 135 is screw threadedly engaged in the wall 79 and projects through the wall 79 into the bellows 76. A suitable cleft 136 is provided in the abutment rod 135 and is positioned exteriorly of the bellows 76 so that the abutment rod 135 may be conveniently adjusted longitudinally for calibration purposes. The abutment rod 135 is arranged so as to engage the plate 82 upon the pressure in the intake manifold decreasing to a predetermined low value equal to the critical standard value at which the automatic control for opening the throttle is to be discontinued and manual control alone remains.

A second abutment rod 137 is also mounted within the bellows 77 as shown in Figure 1, for the purpose of limiting the excessive expansion of bellows 76 and contraction of bellows 77 which might otherwise cause mechanical damage thereto.

There is further provided a third safety means for preventing the automatic opening of the throttle 19 past a predetermined maximum critical point, and the said safety means so arranged that such opening of the throttle past such point, may only be accomplished under the positive manual control of the lever 1.

This function is specifically accomplished by providing the bell crank lever 14, previously described, with a knocker arm 138 arranged for actuating the arm 139. The arm 139, as shown in Figures 1 and 4, is pivotally mounted at one end on an eccentric pin 140 carried by an adjustment screw 141. The adjustment screw 141 is screw threadedly engaged in the wall of the casing 7. The position of the arm 139 in relation to the knocker arm 138 may be conveniently adjusted for calibration purposes by means of the screw 141 which extends through the wall of the casing 7 to the exterior, as shown and described in detail in the copending application of Howard A. Alexanderson Serial No. 783,237, filed October 31, 1947, as a continuation of application Serial No. 508,724, filed November 2, 1943, and now abandoned.

Carried by the arm 139 is a pin 142, on which is mounted a roller 143 arranged for engagement by the knocker arm 138 as shown in Figures 1 and 4. There further projects from the arm 139 a member 144 which is arranged to engage a valve

actuating stop pin 145 slidably mounted within a sleeve member. The stop pin 145 projects through the sleeve into the valve sleeve 56A where it is adapted to engage in its inward position, the free end of the servo control valve rod 56. The pin 145 is normally biased by a spring 146 into a disengaging relation from the rod 56. In the latter position the pin 145 under the biasing force of the spring 146 actuates the arm 139 10 in a counter-clockwise direction against a stop pin 147 mounted in the wall 7. Upon the throttle 19 being opened to a predetermined point the bell crank lever 15 will be positioned so as to cause the knocker arm 138 to engage the roller 143 mounted on the arm 139. Continued clockwise adjustment of the bell crank lever 15 will cause arm 139 to actuate the pin 145 inward so as to prevent control valve rod 56 from being adjusted through the lever 50 to a position to the left of the neutral position. In the latter locked position a decrease in pressure at the intake manifold 20 would cause merely a contraction of the bellows 76 and the actuation of the lever 50 so as to cause the movement of the lever 36 in a counter-clockwise direction against the biasing force of the spring 42. Further clockwise movement of the bell crank lever 15 will cause the pin 145 to actuate the valve rod 56 to the right of the neutral position and the piston 68 to the extreme left hand position shown, whereupon further opening of the throttle valve 19 may be directly effected by manual operation of lever 1.

Operation

From the foregoing arrangement it will be seen that there is provided a novel mechanism for alternately providing two pressure selecting programs from a single datum changing member or cam 33 positioned by the pilot operated control lever 1. Moreover, upon operation of the water or supplemental fluid injection system, the cam follower arm 36 is automatically effected so as to provide a higher pressure setting program than when the system is not in operation. The apparatus may be arranged so that during the operation of the high pressure setting program, the low pressure lock out 135 will not be brought into operation due to the high pressure setting provided. However, during operation of the low pressure setting program the latter lock out 135 may become effective when the lever 1 has been adjusted to within a minimum pressure setting range.

Similarly during the operation of the low pressure setting program, it will be readily seen that within a limited low altitude range the lock out 145 will not become effective due to the relative low selected pressure. The lock out 145 in the latter altitude range will become effective during the operation of the high pressure setting program when the control lever 1 has been adjusted to within a maximum pressure setting range. The lock out 145 may also become effective during operation of either the high or low pressure setting programs at excessively high altitudes or within extremely low atmospheric pressure regions as the throttle 19 is adjusted to extreme open positions to meet the pressure setting.

Although only one embodiment of the invention has been illustrated and described, various changes in the form and relative arrangements of the parts, which will now appear to those skilled in the art, may be made without departing 75 from the scope of the invention. Reference is,

therefore, to be had to the appended claims for a definition of the limits of the invention.

What is claimed is:

1. A regulator for the induction system of a supercharged aircraft engine, comprising, in combination, a boost control for regulating said induction system so as to maintain the pressure thereof at a predetermined value, a cam, a lever connected to said boost control for changing the datum thereof and operably positioned by said cam, a member pivotally mounting said lever, an arm carrying said first mentioned pivot member, a second member pivotally supporting said arm, a spring carried by said second member and biasing said lever about said first mentioned pivot member into contacting relation with said cam, said arm being arranged to shift said first mentioned pivot member against the biasing force of said spring so as to change the pressure selected by said cam.

2. In a boost control, the combination comprising a cam, a cam follower lever operably connected to said boost control for varying the datum thereof, a first member for pivotally supporting said lever, an arm carrying said first member, a second member for pivotally supporting said arm, a spring coiled about said second member and biasing said lever into contacting relation with said cam, and said arm being arranged so as to effect adjustment of said first member from a first to a second position against the biasing force of said spring so as to change the datum of said boost control.

3. In a boost control, the combination comprising a cam, a cam follower lever operably connected to said boost control for varying the datum thereof, a first member for pivotally supporting said lever, an arm carrying said first member, a second member for pivotally supporting said arm, a spring coiled about said second member and biasing said lever into contacting relation with said cam, said arm being arranged so as to effect adjustment of said first member from a first to a second position against the biasing force of said spring so as to change the datum of said boost control, a rod for actuating said arm, a diaphragm affixed to said rod, a spring biasing said rod in one direction and said diaphragm responsive to fluid pressure for actuation of the rod in an opposite direction.

4. In an aircraft internal combustion engine of the type including a carburetor for supplying a combustible mixture to said engine, operable means for injecting a supplemental fluid for suppressing predetonation of said engine, a supercharger for supplying air to the induction system of said engine, a throttle valve for controlling the induction pressure, and a boost control for regulating the throttle valve; the improvement comprising means for changing the datum of said boost control, a pilot's control lever operably connected to said datum changing means, means responsive to operation of said supplemental fluid injection means for actuating said datum changing means from a first to a second datum changing program, means limiting the adjustment of said throttle valve by said boost control, and means connecting said lever and throttle valve so as to effect manual control of said throttle valve within said limited range.

5. In an aircraft internal combustion engine of the type including a carburetor for supplying a combustible mixture to said engine, operable means for injecting a supplemental fluid for suppressing predetonation of said engine, a super-

charger for supplying air to the induction system of said engine, a throttle valve for controlling the induction pressure, and a boost control for regulating the throttle valve; the improvement comprising means for changing the datum of said boost control, a pilot's control lever operably connected to said datum changing means, means responsive to operation of said supplemental fluid injection means for actuating said datum changing means from a first to a second datum changing program, means limiting the adjustment of said throttle valve by said boost control within a predetermined range of adjustment of said lever during the non-operation of said supplemental fluid injection means, and other means limiting the adjustment of said throttle valve by said boost control within a predetermined range during operation of said supplemental fluid injection means, and means connecting said lever and throttle valve for manual control of the throttle valve within said limited ranges.

6. In an aircraft internal combustion engine, the combination comprising operable means for injecting a supplemental fluid for suppressing predetonation of said engine, a throttle valve for controlling engine induction pressure, an induction pressure responsive means for automatically adjusting said throttle valve so as to maintain a selected induction pressure, a pilot's control member for adjusting the selected pressure of said automatic means, means operably connecting said control member to said automatic means, a fluid pressure sensitive membrane connected to said connecting means so as to shift the pressure setting range of said first mentioned automatic means from a first to a second predetermined program, and means operably connecting said membrane to the supplemental fluid injecting means so as to cause an increase in said pressure setting in response to operation of the supplemental fluid injecting means.

7. In an aircraft internal combustion engine, the combination comprising operable means for injecting a supplemental fluid for suppressing predetonation of said engine, a boost control for regulating engine induction pressure so as to maintain the pressure thereof at a predetermined value, a cam, a pilot's control member to adjust the cam, a lever connected to said boost control for changing the datum thereof and operably positioned by said cam, a member pivotally mounting said lever, means for shifting said pivot member from a first to a second position so as to change the datum changing program of said boost control from a first to a second predetermined program, a fluid pressure sensitive membrane operably connected between said last mentioned means and said fluid injecting means to cause the shifting of the pivot member upon operation of said supplemental fluid injecting means.

8. In an aircraft internal combustion engine, the combination comprising operable means for injecting a supplemental fluid for suppressing predetonation of said engine, a boost control for regulating engine induction pressure so as to maintain the pressure thereof at a predetermined value, a cam, a pilot's control member to adjust the cam, a lever connected to said boost control for changing the datum thereof and operably positioned by said cam, a member pivotally mounting said lever, means for shifting said pivot member from a first to a second position so as to change the datum changing program of said boost control from a first to a second predetermined

program, and a spring biasing said lever into contacting relation with said cam and opposing movement of said pivot member from said first to said second position, said pivot shifting means including a fluid pressure sensitive membrane for actuating said pivot member from the first to the second position, and means operably connecting the membrane to said fluid injecting means.
